UNITED STATES PATENT OFFICE.

SAMUEL E. DIESCHER, OF PITTSBURG, PENNSYLVANIA, ASSIGNOR TO EMIL WINTER, OF PITTSBURG, PENNSYLVANIA.

HOUSING FOR ROLLING-MILLS.

No. 907,135.

Specification of Letters Patent.

Patented Dec. 22, 1908.

Application filed January 14, 1907. Serial No. 352,264.

To all whom it may concern:

Be it known that I, SAMUEL E. DIESCHER, residing at Pittsburg, in the county of Allegheny and State of Pennsylvania, a citizen 5 of the United States, have invented or discovered certain new and useful Improvements in Housings for Rolling-Mills, of which improvements the following is a specification.

The invention described herein relates to 10 certain improvements in mills for swaging billets.

It has heretofore been the practice to 15 mount the swaging rolls in one pair of housings and the pinions employed for transmitting the desired oscillatory movement to the swages, in another pair of housings. The thrust which the crank arms operated by the 20 pinions exert on the crank-arms connected to the swages, exerts so great disturbing influence, that the maintenance of the proper 25 relative position of the housings of the swages and pinions is a source of great expense and the cause of frequent interruptions in the operation of the mill.

The invention described herein consists in 30 providing a housing with windows or openings for the reception of the bearings of the rolls and pinions, so that said parts will be mounted in an integral structure.

The invention is hereinafter more fully described and claimed.

In the accompanying drawings forming a 35 part of the specification, Figure 1 is a side elevation of a housing embodying my improvement; Fig. 2 is a similar view illustrating a modification of my invention, and Fig. 3 is a sectional plan view on a plane indicated by the line III—III Fig. 1.

In the practice of my invention, the housings 40 1 are made of sufficient width to permit of the formation of windows or openings 2 and 3 for the reception of the journal blocks 4 and 5 for the swages 6 and driving pinions 8. In the construction shown in Fig. 1 the 45 windows are made sufficiently wide to per-

mit of the endwise insertion of the pinions and swages through them. If however the housings are constructed with a removable cap 9 as shown in Fig. 2, the windows need not be made of so great a width. Where the 50 pinions 8 are driven by means of a pinion 10 of the power shaft, it is preferred that the housings should be made sufficiently wide to permit of the formation therein of a window or opening 11 for the reception of the 55 journal blocks 12 of said transmitting pinion 10. As the driving pinions should intermesh so as to insure synchronous movements of the swages, provision is made for the passage of the article operated on between the 60 pinions by cutting peripheral grooves 13 in the pinions, in the line of feed of the article. It is preferred to also employ a guiding tube 14, to prevent the article being caught by the pinions. The pinions have counterbalanced 65 arms 15 secured on their journals, and the pins 16 on said arms are connected to pins 17 on counterbalanced arms 18 on the journals of the rolls. When the housings are constructed with removable caps, the latter and 70 the body of the housings are preferably constructed so as to interlock one with the other, thereby relieving the bolts 19 from transverse or shearing strains.

I claim herein as my invention: 75

Housings for rolls having windows or openings for the rolls and driving pinions formed in an integral structure in combination with rolls having their journals mounted in two of said windows, driving pinions having their 80 journals mounted in the other windows and crank and pitmen connections from the pinions to the rolls.

In testimony whereof, I have hereunto set my hand.

SAMUEL E. DIESCHER.
